(57) **CLAIM**

The ornamental design for a smoke detector, as shown and described.

DESCRIPTION

FIG. 1 is a perspective view of a first embodiment of a smoke detector.

FIG. 2 is a first side view of the embodiment shown in FIG. 1.

FIG. 3 is a second side view of the embodiment shown in FIG. 1.

FIG. 4 is a third side view of the embodiment shown in FIG. 1.

FIG. 5 is a fourth side view of the embodiment shown in FIG. 1.

FIG. 6 is a top view of the embodiment shown in FIG. 1.

FIG. 7 is a bottom view of the embodiment shown in FIG. 1.

FIG. 8 is a perspective view of a second embodiment of a smoke detector.

FIG. 9 is a first side view of the embodiment shown in FIG. 8.

FIG. 10 is a second side view of the embodiment shown in FIG. 8.

FIG. 11 is a third side view of the embodiment shown in FIG. 8.

FIG. 12 is a fourth side view of the embodiment shown in FIG. 8.

FIG. 13 is a top view of the embodiment shown in FIG. 8; and,

FIG. 14 is a bottom view of the embodiment shown in FIG. 8.

The broken lines in the drawings depict portions of the smoke detector that form no part of the claimed design.
